CLAIM

The ornamental design for a red wine cabinet, as shown and described.

DESCRIPTION

FIG. 1 is a front view of a red wine cabinet showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is an enlarged front elevation view of the detail identified in FIG. 1; and,

FIG. 8 is a front view of the red wine cabinet, shown within an environment of use.

The broken line illustrate portions of the red wine cabinet and form no part of the claimed design. In FIG. 8, the broken line depicting a red wine bottle represents environmental subject matter that forms no part of the claimed design.
